Delmar D. Rhoads, 3230 S. Calhoun St., Fort Wayne, Ind.

Filed Sept. 17, 1958, Ser. No. 52,673

Term of patent 14 years

(Cl. D14—3)

Figure 1 is a perspective view of a combination hot and cold food transportation and serving cart with the lids open showing my new design;

Figure 2 is a front elevational view of the serving cart illustrated in Figure 1 with the doors closed and lids closed;

Figure 3 is an end view of the serving cart illustrated in Figure 2;

Figure 4 is a top plan view of the serving cart illustrated in Figure 2.

The rear not shown is substantially plain, and the end not shown is like the end shown.

I claim:

The ornamental design for a combination hot and cold food transportation and serving cart, as shown and described.
